BICYCLE CHAIN GUARD

Viktor Schreckengost, Cleveland Heights, Ohio, assignor
to The Murray Ohio Manufacturing Co., Nashville,
Tenn.

Filed June 24, 1970, Ser. No. 23,647

Term of patent 14 years

Int. Cl. D12—14

U.S. Cl. D90—5

Fig. 2

Fig. 3

FIG. 1 is a side elevational view of a bicycle chain guard showing my new design;

FIG. 2 is a top plan view thereof;

FIG. 3 is a bottom plan view thereof;

FIG. 4 is a front elevational view thereof; and

FIG. 5 is a rear elevational view thereof.

I claim:

The ornamental design for a bicycle chain guard, substantially as shown.
